ROTARY ENGINE

Joseph F. Jaworowski, Cleveland, Ohio, assignor
of twenty-five per cent to Samuel E. Dettel-
bach and twenty-five per cent to Sam Emerson,
both of Cleveland, Ohio

Application November 25, 1932, Serial No. 644,199

2 Claims. (Cl. 103—144)

My invention relates to an improvement in rotary engines, and more particularly to a pump or compressor comprising a circular working chamber in which a rotary piston is adapted to operate to compress or transfer a liquid or other fluid. The general object of the present invention is to provide a smooth running pump structure, which may be constructed at low costs and easily assembled and disassembled, wherein a high degree of pumping efficiency may be maintained and the life and durability of the working parts prolonged by cushioning and dampening the oscillations of the suction or intake side of the pump in such a degree that the rotating blades of the pump will rotate with little or no vibration, when the pump is running.

In the accompanying drawings, in which I show a preferred form of pump embodying the invention:

20 Figure 1 is a transversal sectional view of the pump taken on line 1—1 of Figure 2 and showing the working chamber and cylindrical drive member in elevation;

25 Figure 2 is a longitudinal sectional view on line 2—2 of Figure 1;

Figures 3 and 4 are front and side elevations of the bearing member forming part of the drive member;

30 Figures 5 and 6 are front and longitudinal sectional views of the driving member, Figure 6 being taken on line 6—6 of Figure 5;

Figure 7 is a transversal sectional view of the pump taken on line 7—7 of Figure 2;

Figures 8, 9 and 10 are longitudinal sectional 35 views of the pump body and cover members when disassembled;

Figure 11 is a side view of the stud shaft supporting the driving member; and

Figures 12 and 13 are side views of the male 40 and female blades of the driving member.

Referring specifically to the drawings in which like reference characters designate like parts throughout the several views the pump comprises a cast metal body 2, having flat side walls 3 and a circular opening 4 extending centrally therethrough. An intake passage 5 and a discharge passage 6 communicate with circular opening or cylinder chamber 4, and these passages are separated from each other by a transverse wall 7. 45 Passages 5 and 6 are at their outer ends encircled by tapped flanged portions 8 and 9, respectively, which support plates 10 and 11 secured thereto by means of set screws 12. Plates 10 and 11 are provided with axial threaded openings 14 and 15 for inlet and outlet pipes 16, 17

which thus communicate with circular opening or cylinder 4. Separate cover plates 18 and 19 detachably bolted to the flanged side walls 3 of body 2 enclose the opposite ends of circular chamber or cylinder 4. A chamber 20 formed 60 in body 2 adjacent inlet passage 5, serves to damp suction oscillations at the intake side of the pump, thus reducing chattering to a minimum. Chamber 20 communicates with inlet passage 5 and cylinder 4 through a transverse 65 opening or passage 21 formed between the edge 22' of a longitudinal curved separating wall 22, and projecting inwardly and downwardly from flanged portions 8, and the edge 2' of body 2, which body portion is interrupted at this point 70 to provide communication between cylinder 4 and passage 5. The chamber 20 extends upwardly and outwardly within the confines of curved wall 22 and above opening or passage 21, thus forming an air or gas cushioning pocket 75 which serves to counteract suction oscillations at the intake side of the pump caused by the variations in suction of the rotor 24 and its set of piston blades 25. This insures a steady flow of liquid through inlet passage 5 into cylinder 4. 80 As shown the central portion of the edge 22' of the longitudinal curved separating wall 22 between chamber 20, inlet passage 5 and cylinder 4 is centrally recessed along converging lines. Consequently the opening or passage 21 decreases gradually in depth from its longitudinal center towards its ends, an arrangement which facilitates damping of both large and small pressure oscillations.

85 The flow of the fluid during operation of the pump is effected by the piston blades 25 and cylindrical rotor 24 adapted to revolve or be revolved within cylinder 4. Rotor 24 is of smaller diameter than the circular chamber or cylinder 4 and it rotates on a fixed axis offset or eccentric to the axis of cylinder 4 so that the periphery of the rotor is always in close contact with the inner wall 7 intermediate intake and discharge openings 5 and 6, respectively thus cutting off direct communication between said passages and providing a crescent-shaped working chamber 27 within the cylinder 4 around rotor 24. The working chamber is divided radially into separate working compartments by three piston blades 25, one male blade and two female blades, which extend through longitudinal slots 28 in the cylindrical wall of cylindrical rotor 24. The outer end edges of these blades are curved to approximately the same radius as the inner curved wall of cylinder 4 and the inner ends of these blades are 100 105 110

hinged together or pivotally connected to a bushing 29 adapted to rotate about a pin or shaft 30, the axis of which is co-incident with the axis of cylinder 4 so that the piston blades may always 5 maintain their radial position and rotate freely upon the axis without binding against the wall of cylinder 4. The cylindrical rotor 22 is mounted at one end upon a shaft 31 having rotatable bearing in a boss or extension 32 on cover plate 19 10 and this shaft extends through an adjustable packing gland 32' and is adapted to be driven by power in any desirable way.

The rotation imparted to rotor 24 drives the radial piston blades 25 in a circular path within 15 cylinder 4, and constant contact of the rotor with the blades is established near the outer ends of the blades where they pass through the slots 28 in the rotor. The sides of these slots are ground to reverse inclinations to provide narrow crests 33 20 on opposite sides of the blades and the inner end of each slot is enlarged and the rotor itself made hollow in part to permit the inner ends of the blades to assume different angular positions in respect to rotor 24.

25 When the rotor revolves, the off center position of rotor 24 within cylinder 4 causes the piston blades to oscillate in respect to each other and the rotor and a relative sliding movement also occurs between the rotor and the piston blades which are 30 merely oscillated on the fixed pin or shaft 30 as they are forced to travel in a circular path or orbit by the rotatable movement of the rotor on its own axis which is off center to the common axis for the cylinder and blades. A predetermined 35 amount of fluid may thereby be pumped or transferred from the intake passage to the discharge passage through the crescent shaped working chamber 27 during each revolution of the rotor.

40 The pin or shaft 30 to which the piston blades are hinged is an integral offset extension of a short shaft 34 which latter shaft is held against rotation within a hub portion 35 on cover plate 18, a pin 36 being used for such purpose. One end 45 of the rotor is open and provided with a series of symmetrically arranged recesses 37 which seat laterally arranged extensions 38 of a sleeve or bushing 39. This bushing member fits short shaft 34 adjacent its offset portion 30 and is secured 50 to said rotor by means of set screws 40.

The piston blades 25 are provided with wing portions 41 adapted to operate within the longitudinal slots 28 the full length of the rotor. That is to say, the working areas of the blades are co-extensive with the cylinder 4 in pump body 2, which places the end edges of the wing portions of the blades in a relatively close seating position against the flat inner walls of the cover plates 18 and 19. The narrow end portions of the 60 piston blades provide hinge portions, which in the male piston blade embodies a single hinge 42, whereas the female piston blades show two spaced hinges 43, 43'. These hinged portions are sleeved over the bushing 29 which is sleeved over the stationary shaft or pin 30 extending axially into the cylinder 4. When the parts are assembled the connecting hinge portions for the piston blades are confined between rotor 24, and the closed hub end 44 of said rotor, but are spaced apart therefrom to permit the blades to oscillate freely.

The described arrangement of a suction equalizing chamber at the intake side of a pump of the

kind described, in close proximity or adjacent to the cylinder and communicating with the latter adjacent the point where the blades begin their suction action, eliminates the chattering of the blades and prevents their working against the driving rotor because the high and low peaks of the suction oscillations which commonly cause chattering are damped or flattened out. A very quiet and steady pumping action with a minimum of wear between the blades, rotor and cylinder walls is thus effected. Chattering and other undesirable effects on the working parts of a pump due to vaporization of commonly known high test gasolines which have the tendency to partly vaporize under relatively low pressure are practically eliminated due to the fact that vapor is sucked from passage 5 into the chamber 20, where it is at rest sufficiently long to permit partial or complete condensation to take place each time a piston blade 25 reaches the point 2' of the cylinder wall or body 2, and cuts off communication between chamber 27 and the inlet or suction side of the pump. As this point is passed by the piston blade, the suction action of the blade pulls gasoline both from chamber 20 and chamber 5 into 100 chamber 27. Chamber 20 thus serves as an expansion or suction equalizing chamber, in that part of the fast moving body of gasoline is directed away from the back of the piston blade and into the chamber 20, thus eliminating the 105 tendency of this moving body to back up against or slap the piston blade with chattering effect. The elimination of vapor from the gasoline passing through the pump, cuts down the tendency of the blades to chatter and permits of greater accuracy in metering the quantity of gasoline dispensed.

Having thus described my invention, what I claim is:

1. A high speed rotary pump including a circular chamber, an intake passage for said chamber extending laterally therefrom, a rotary member offset centrally within said chamber, piston blades carried by said rotary member within said chamber, and a suction oscillation equalizing chamber 120 adjacent to said circular chamber below said intake passage, said equalizing chamber communicating with said intake passage and said circular chamber through an elongated opening formed in the middle portion of the inner side 125 wall of said equalizing chamber, said opening being formed at the end of said intake passage and adjacent to said circular chamber by laterally offsetting the top portion of said inner side wall with respect to the lower portion thereof. 130

2. A high speed rotary pump including a circular chamber, an intake passage for said chamber extending laterally therefrom, a rotary member offset centrally within said chamber, piston blades carried by said rotary member within said chamber, and a suction oscillation equalizing chamber adjacent to said circular chamber below said intake passage, said equalizing chamber communicating with said intake passage and said circular chamber through an elongated opening formed in 140 the middle portion of the inner wall of said equalizing chamber by laterally offsetting the top portion of said inner wall with respect to the lower portion thereof, and the width of said opening decreasing toward the opposite ends thereof. 145

JOSEPH F. JAWROWSKI.
